UNITED STATES PATENT OFFICE.

GEORGE P. WIGGINTON, OF KALAMAZOO, MICHIGAN, ASSIGNOR, BY MESNE ASSIGNMENTS, TO REMINGTON RAND INC., OF NEW YORK, N. Y., A CORPORATION OF DELAWARE.

BINDER.

Application filed April 7, 1924. Serial No. 704,655.

This invention relates to improvements in binders.

My improved binder is designed for the binding of sheets permanently and is particularly designed by me for the permanent binding of sheets which have been used in loose sheet accounting, but which it is desired to preserve for permanent record. My improved binder is, however, desirable for use in the binding of any sheets, catalogs or the like.

The main object of this invention is to provide an improved binder which is simple and economical in its parts and one which may be quickly assembled to permanently bind and secure the sheets.

A further object is to provide an improved binder having these advantages from which it is quite impossible to release the sheets without destroying the binder or the sheets.

Objects pertaining to details and economies of construction and operation of my improvements will definitely appear from the detailed description to follow.

I accomplish the objects of my invention by the devices and means described in the following specification. The invention is clearly defined and pointed out in the claim.

A structure embodying the features of my invention is clearly illustrated in the accompanying drawing forming a part of this application, in which:

Fig. I is a perspective view of a binder embodying the features of my invention.

Fig. II is a detail vertical section on a line corresponding to line 2—2 of Fig. I.

Fig. III is a detail horizontal section on a line corresponding to line 3—3 of Fig. II.

In the drawing the sectional views are taken looking in the direction of the little arrows at the ends of the section lines and similar numerals of reference indicate similar parts in all of the views.

Referring to the drawing, the sheets 1 have perforations 2 therein to receive binding posts. My improved binder comprises a pair of binder bars 3 and 4 secured to the covers 5 by the hinges 6. These binder bars are secured in clamping relation to the sheet

by means of the binding posts comprising a 50 relatively fixed member designated generally by the numeral 7 which is made up of sections 8, 9 and 10, the bottom section 8 being riveted to the bottom binder bar. The section 10 is a terminal section while one or 55 more of the sections 9 are used, as may be desired.

The terminal section 10 has a plurality of annular grooves 11 formed therein forming annular ratchet teeth 12. The coacting post 60 member 13 is arranged through the hole 14 in the binder bar 3 and has a head 15 engaging the outer side of the binder bar. This post section is tubular and longitudinally slotted at 16 providing a plurality of spring 65 pawls 17, the inner ends of the pawls being turned inwardly at 18 to engage the ratchet teeth of the terminal member 10.

With the parts thus formed the post 7 is built up to the desired length, that is, to accommodate the particular body of sheets which it is desired to bind, the sheets are arranged thereon, the binder bar 3 superimposed and the post member 13 introduced thereto and forced downwardly as far as 75 possible, clamping the top binding member upon the sheets and permanently securing the parts together, as it is impossible to disengage the ratchet teeth, the same being engaged and held by the sheet body so that 80 they cannot be sprung outward without such mutilation of the sheet body or the binders as to practically destroy the same. My improved binder is very economical in its parts, 85 may be quickly adjusted to the sheet body, and securely and permanently binds the same.

Having thus described my invention what I claim as new and desire to secure by Letters Patent is:

The combination in a binder for sheets 90 perforated to receive binding posts, of binder bars, a binding post secured to the bottom binder bar and having a plurality of external annular grooves providing 95 ratchet-like annular teeth detachably connected to said base section, and a coacting tubular member disposed through the upper

binder bar to telescopingly embrace said terminal section, said tubular member being longitudinally slitted providing a plurality of spring pawls having inturned ends coacting with the said teeth when the parts are telescoped within the said body, the perforations in said sheet body being of such

diameter as to closely embrace said tubular member preventing disengagement of said spring pawls.

10

In witness whereof I have hereunto set my hand.

GEORGE P. WIGGINTON.
